PHONOGRAPH

Robert F. Mansfield, Tokyo, Japan, assignor to Capehart Corporation, New York, N.Y.

Filed Sept. 18, 1972, Ser. No. 290,073

Term of patent 14 years

Int. Cl. D14—01

U.S. Cl. D56—4 R

FIG. 1

FIG. 2

FIG. 3

FIG. 4

FIG. 5

FIG. 1 is a front, top and right side perspective view of a phonograph showing my new design;

FIG. 2 is a front elevational view;

FIG. 3 is a right side elevational view;

FIG. 4 is a top plan view; and

FIG. 5 is a bottom plan view.

The rear of the phonograph is plain and unornamented. I claim:

The ornamental design for a phonograph, as shown and described.
